UNITED STATES PATENT OFFICE.

FREDERICK CARON, OF DETROIT, MICHIGAN.

SHADE-BRACKET.

1,267,182.

Specification of Letters Patent. Patented May 21, 1918.

Application filed August 25, 1917. Serial No. 188,105.

To all whom it may concern:

Be it known that I, FREDERICK CARON, a citizen of the United States, residing at Detroit, in the county of Wayne and State of Michigan, have invented new and useful Improvements in Shade-Brackets, of which the following is a specification.

This invention has reference to a window fixture designed to support a curtain pole 10 and a shade roller.

An object of the invention is to produce an article of this character which may be easily and quickly attached to the side molding of a window casing, without the employment of nails, screws or analogous devices, and which when so attached, may remain a rigid and permanent fixture.

A further object of the invention is to produce a device of this character which 20 will readily adjust itself to various sizes of moldings on window casings, which shall be of a simple construction, readily attached without the aid of tools, cheap to manufacture, and thoroughly efficient in operation.

With the foregoing objects in view, the improvement resides in the construction, combination and operative arrangement of parts set forth in the following description and falling within the scope of what is 25 claimed.

In the drawing,

Figure 1 is a perspective view illustrating the application of the improvement.

Fig. 2 is a rear elevation of the same.

Fig. 3 is a sectional view approximately 35 on the line 3—3 of Fig. 1.

Fig. 4 is an approximately central longitudinal sectional view through the improvement.

Fig. 5 is a detail sectional view approximately on the line 5—5 of Fig. 1.

My improvement contemplates the employment of two angular plates 5 and 6 respectively, the plate 5 being in the nature 45 of a stationary member, while the plate 6 is movable longitudinally of the plate 5.

The plate 5 preferably has the edges of its straight outer portion turned inwardly and over the inner face of the said plate providing ways 7 receiving the longitudinal edges of the inner plate 6, and providing guides for the said inner plate. The angular end of the outer plate, indicated for distinction by the numeral 8 preferably has its 55 outer edges of its sides beaded as at 9, whereby to effectively reinforce the said member

8 and the outer end of the said member 8 is provided with spaced inturned angular teeth 10.

Passing through suitable threaded openings in the outer face of the plate 5 are the threaded shanks of headed members 11, the said headed members being received in elongated slots 12 formed upon the body portion 13 of a bracket 14, the angular end of the 60 said bracket being provided with a suitable opening to receive the pintle of a shade roller, while formed upon the outer end of the plate 5, or the end thereof, opposite the angular element 8 is an outturned angular 65 bracket 15, the same being designed to receive a pole supporting a window curtain.

The angular end 16 of the plate 6 is of a greatly less length than the angular end 15 of the plate 5, the said end 16 having inturned spaced teeth 17. The longitudinal edges of the plate 6, are, for a suitable distance from the ends of the said plate provided with cut away portions so that the central portion of the plate is reduced in 70 width and the longitudinal edges thereof are provided with teeth 18.

Pivotedly secured in the guide ways 7 of the plate 5, as at 19, are the heads 20 of levers 21, the said heads being each provided 75 with a tooth 22 designed to engage with the teeth 18 on the inner plate 6, when the levers are swung toward the plate 5. The heads of the levers are arranged in suitable openings in the outer edges of the guide ways, as 80 clearly shown by the drawings.

Formed upon the outer edge of the plate 5, or the edge thereof, provided with the bracket 15, are outwardly extending members 23, in the nature of fingers and having 95 their ends inturned as at 24, providing hooks and these hooks are designed to engage with the ends of the levers 21 when the said levers are swung to bring their teeth 22 in locking engagement with the teeth 18.

It is thought, from the foregoing description, when taken in connection with the drawing, the simplicity and advantages of the construction will be apparent, to those skilled in the art, without further detailed description, it being noted that the plate 6 is moved outwardly of the plate 5 until the angular ends of both the plates 5 and 6 are brought to contacting engagement with the opposite edges of the vertical molding of the 100 window casing, and may, by the hand of the operator, be brought tightly against said 110

molding, so that the teeth or spurs 10 and 17 will partly enter the said casing. The levers which are swung outwardly to inoperative position, are now turned upon their 5 pivots toward the longitudinal edges of the plate 5, which movement, causing the teeth on the heads of the said levers to engage with the teeth of the inner plate 6, will move the said inner plate inwardly of the outer 10 plate, forcing the spurs on the angular ends of both of the said plates into the opposite edges of the molding, and as the levers are designed to be engaged by the hooks 24, the plates 5 and 6 are effectively retained in 15 locked position. The bracket 14, through the medium of the slots 12, in the body thereof, and the co-engagement of the headed members 11 may be adjusted longitudinally over the plate 5, so that shade rollers of different lengths may be thus accommodated. 20

Having thus described my invention, what I claim is:

A shade bracket including two members each having an angular outer end provided

with inturned teeth, the outer member having its longitudinal edges turned over its back to provide ways receiving the inner member, said outer member, approximately central of its longitudinal edges having slots communicating with the ways, and having its end opposite its angular end provided with oppositely extending hooks, the beaks of which being inturned, the inner member being centrally depressed from its longitudinal edges and the longitudinal edges provided by the said depressed portions being toothed, a lever having an offset head arranged in each of the slots and pivotally secured to the outer plate, each of said heads having a tooth designed to engage with the teeth on the reduced portion of the inner member, and said levers designed to be engaged by the referred to hooks to hold the teeth thereof in engagement with the teeth of the inner member.

45

In testimony whereof I affix my signature.

FREDERICK CARON.
